United States Patent Office.

J. E. WIGGIN AND DANIEL G. CROSBY, OF STONEHAM, MASSACHUSETTS.

Letters Patent No. 63,846, dated March 26, 1867.

IMPROVED HEEL-SHAVING GUARD.

The Schedule referred to in these Letters Patent and making part of the same.

TO ALL WHOM IT MAY CONCERN:

Be it known that we, J. E. WIGGIN and DANIEL G. CROSBY, both of Stoneham, in the county of Middlesex, and State of Massachusetts, have invented an Improved Centre for Heel-Shaving Machine Guard; and we do hereby declare that the following is a full and exact description thereof, reference being had to the accompanying drawings, and to the letters of reference marked thereon.

Nature.

The nature of our invention consists in the application of the ball-and-socket joint to the guard of heel-shaving machines.

To enable others skilled in the art to make and use our invention, we will proceed to describe its construction and use.

Drawings.

Figure 1 is an elevation showing the guard A, and centre B, as it appears when working.

Figure 2 is an elevation showing the guard A attached to the heel of the shoe.

Figure 3 represents the centre.

Figure 4 represents a plan of the heel-guard and centre B.

Figure 5 is a section through the middle of the guard and centre.

The guard A is made of any suitable metal, and in general of the shape represented in the drawings, which agree in form with those used in connection with the heel-cutting machine patented by O. G. Critchett, June 21, 1864. B represents a "centre;" the form of this "centre" is shown in section in fig. 5. Upon the end of this "centre" the ball C is attached by the washer D, which is riveted firmly to the "centre;" the ball C is free to revolve independently of the other part of the "centre."

The use of our invention is obvious, as it takes the place of the "centre" in common use for this purpose. The advantage is this: the shoe is always kept in the proper relative position, so that the heel may be trimmed rapidly with great precision and ease.

Claim.

What we claim as our invention, and desire to secure by Letters Patent of the United States, is—

1. The combination and arrangement of the guard A and pin B, when the two are constructed substantially in the manner described.
2. We claim the device of the ball-and-socket joint, when combined with the guard and "centre" of a heel-trimming machine.

J. E. WIGGIN,
DANIEL G. CROSBY.
